Application filed June 6, 1900. Serial No. 19,327. Term of patent 7 years.

To all whom it may concern:

Be it known that I, CHRISTIAN SEIDEL, a citizen of the United States, residing at New York, in the borough of Bronx and State of New York, have invented and produced a new and original Design for Skirt-Protectors, of which the following is a specification, reference being had to the accompanying drawing, which shows a portion in side elevation.

The leading or material features of my design are small trinal figures, extending longitudinally of the skirt-protector and arranged in diagonal rows, and small bead-like figures interspersed regularly therewith and extending transversely across.

a indicates the small trinal figures extending longitudinally of the skirt-protector, and b the small bead-like figures interspersed therewith.

Along one side portion of the protector there extends a ribbed or regularly-beaded longitudinal portion c, and along the other side portion extends a ribbed or beaded longitudinal portion d, a chain-like portion e, another ribbed or beaded portion f, and a fringe-like portion g.

What I claim is—

The design for a skirt-protector, as shown and described.

In testimony that I claim the foregoing as my invention I have signed my name in presence of two subscribing witnesses.
